UNITED STATES PATENT OFFICE.

JOHN DOUGLAS, OF ELIZABETH, NEW JERSEY, ASSIGNOR TO THE SINGER MANUFACTURING COMPANY OF NEW JERSEY.

CUTTING MECHANISM FOR BUTTON-HOLE SEWING-MACHINES.

SPECIFICATION forming part of Letters Patent No. 367,796, dated August 9, 1887.

Application filed September 21, 1886. Serial No. 214,151. (No model.)

To all whom it may concern.

Be it known that I, JOHN DOUGLAS, a citizen of the United States, residing at Elizabeth, in the county of Union and State of New Jersey, have invented certain new and useful Improvements in Cutting Mechanism for Button-Hole Sewing-Machines, of which the following is a specification, reference being had therein to the accompanying drawings.

10 The object of my invention is to provide a convenient button-hole-cutting device for use with button-hole sewing machines or attachments, the said device being adapted to cut the button-hole, either before or after it has 15 been worked, while the material is held in the clamp, and without removing the clamp from working position on the machine. To this end I pivotally attach a knife-carrying arm or lever to a plate on which the work- 20 clamp is guided, or to a bracket secured to said plate, the knife carried by the said arm being thus at all times in alignment with the center of the button-hole stitching, so that when the work is moved to the proper position 25 longitudinally, as when the stitching for a button-hole has been completed, the knife-carrying lever may be depressed to cut the button-hole before the work is removed from the clamp. In connection with the cutting- 30 lever and the guiding-plate to which it is attached I provide a throat-plate having a slot of proper length to receive the cutting-knife as the latter is forced downward in cutting, the parts of said plate contiguous to said slot 35 supporting the work against the downward thrust of the knife, so that the latter will make a clean smooth slit.

In the drawings, Figure 1 is a front end view of the "Singer" overseaming-machine 40 with my invention applied thereto. Fig. 2 is a partial plan view of the bed-plate with the work-clamp and co-operating parts in position. Fig. 3 is a similar view with the work-clamp removed. Fig. 4 is a section on line 4-4, Fig. 45 3. Fig. 5 is a cross-section of the throat-plate on line 5-5, Fig. 3; and Fig. 6 is a sectional detail of the support for the cutter-carrying lever.

A denotes the work-clamp, which is guided 50 to move lengthwise of the button-holes in

ways formed in a carrying-plate, B, the latter being in turn fitted to slide longitudinally of itself (or transversely of the button-holes) in ways in or on the machine bed-plate C, the sliding movement of the said plate B being for 55 the purpose of shipping over the work to bring the second side of the button-hole beneath the needle after the first side thereof has been stitched.

In the machine to which I have shown my 60 invention as being applied the needle d and needle-bar D are reciprocated horizontally to effect the overseaming or button-hole stitches by mechanism which is or may be the same as that shown by Patents Nos. 272,126 and 319,801 65 to Philip Diehl, and the mechanism for imparting the feeding and ship-over movements to the work-clamp is essentially the same as in the said Patent No. 319,801, the connections between the shipper-lever and the carrying- 70 plate B being, however, in the machine herein shown beneath the bed-plate instead of above the latter, as in the said Patent No. 319,801. The work-clamp A is provided with a spring-depressed pin, a, entering a slot, e, in a plate, 75 E, sliding in ways in the bed-plate C.

To the button-hole-working mechanism above described I have applied my button-hole-cutting mechanism, which consists, essentially, of the cutter-carrying arm or lever 80 F, the cutter or knife f, and the slotted throat-plate G. The lever F is hinged to a bracket, b, secured to the carrying-plate B, the said bracket being provided with a stud, b', around which is coiled a spring, b², which serves to 85 lift the said lever after it has been depressed and to hold it up, the upward movement of the said lever being limited by a stop, consisting in the present instance of a stud, h, attached to the head of the overhanging arm. 90

The knife f is preferably V-shaped or pointed in its center, as shown, and to cut button-holes of different sizes interchangeable knives of different lengths may be employed. The stud b' is preferably of proper length to serve as a 95 stop to limit the downward movement of the lever F in cutting the button-holes.

The throat-plate G is fitted in dovetailed ways in the plate B, so that it may be readily removed when desired. I is a sliding latch, 100

the inner end of which enters a notch in the side of the throat-plate to secure the latter in place. That portion of the throat-plate in which is formed the slot *g* for the entrance of the cutter or knife *f* is raised slightly above the body of the said plate, so that the fabric to be cut will be drawn tightly across the said raised or supporting portion to facilitate the cutting operation and insure a smooth severance of the fabric. This result is due to the fact that the raised portion of the throat-plate comes within the opening of the upper jaw of the clamp when the button-hole is finished and the clamp is in position for the cutting operation, so that the said jaw spans the said raised portion, and thus presses on the fabric on opposite sides of the place where the slit is to be made, and thus the fabric to be cut is drawn tight, as above stated.

As is well known to those skilled in the art to which my invention relates, it is customary to cut what is known as "straight" machine-made button-holes (or button-holes having no eye or eyelet) after the stitching to "work" the button-holes has been completed, and when in the operation of the device herein shown the stitching of a button-hole is finished the work-clamp will be in the forward position, (shown in Figs. 1 and 2,) with the work beneath the cutter or knife *f*, so that the operator, by simply pressing on the lever *F* before removing the work from the clamp, will force the said knife downward and cut the button-hole.

As the knife-carrying lever *F* is connected with the plate *B*, by which the clamp is guided, it will of course follow the lateral movements of the said plate, so that it will always be in proper alignment with the center of the button-hole, (or, more properly, the center of the stitching for the same,) and will also retain its proper position relative to the cutting-slot *g* of the throat-plate *G*, the latter being carried by and thus moving laterally with the plate *B*.

Having thus described my invention, I claim and desire to secure by Letters Patent—

1. The combination, with a button-hole work-clamp and a laterally-movable carrying-plate in or on which the said clamp is guided lengthwise of a button-hole independently of the movements of said plate, of a slotted throat-plate and a cutter-carrying lever, both of

which are laterally movable with the said carrying-plate, substantially as set forth.

2. The combination, with a button-hole work-clamp, a movable carrying-plate in which the said clamp is adapted to be fed lengthwise of a button-hole independently of the movements of the said plate, and a slotted throat-plate removably attached to said carrying-plate, of a cutter-carrying lever connected to and thus movable with the said carrying-plate, substantially as set forth.

3. The combination, with a laterally-movable carrying-plate and a button-hole work-clamp movable lengthwise of a button-hole independently of said plate, of a slotted throat-plate and a bracket, both of which are movable with said carrying-plate, and a cutter-carrying lever hinged to said bracket, substantially as set forth.

4. The combination, with a laterally-movable carrying-plate and a button-hole work-clamp movable lengthwise of a button-hole independently of said plate, of a slotted throat-plate and a cutter-carrying lever, both of which are movable with said carrying-plate, a spring for lifting said lever, and stops for limiting the upward and downward movements thereof, substantially as set forth.

5. The combination of the carrying-plate, the removable throat-plate having a side notch, and the sliding latch for securing the said throat-plate in place, substantially as set forth.

6. The combination, with the work-clamp, the button-hole knife or cutter and its carrying device, of the throat-plate having a raised or supporting portion to be spanned by the upper jaw of the said clamp and provided with a slot for the reception of the said cutter, substantially as set forth.

7. The combination, with a carrying-plate and a work-clamp movable lengthwise of a button-hole independently of said plate, of a slotted throat-plate, a V-shaped or centrally-pointed cutting-knife, and a carrier for the latter, substantially as set forth.

In testimony whereof I affix my signature in presence of two witnesses.

JOHN DOUGLAS.
